(57) **CLAIM**

The ornamental design for a wall faucet, as shown and described.

DESCRIPTION

FIG. 1 is a front elevation view of a wall faucet.

FIG. 2 is a rear elevation view thereof.

FIG. 3 is a left side view thereof.

FIG. 4 is a right side view thereof.

FIG. 5 is a top plan view thereof.

FIG. 6 is a bottom plan view thereof.

FIG. 7 is a perspective view of a wall faucet showing my new design; and,

FIG. 8 is an elevation view showing one application of the present invention, where those environmental features illustrated in dashed lines are not claimed in the present invention.
